WASTE HOPPER

Clifford R. Granberry, Dallas, and Bobby Don Abbott,
Josephine, Tex., assignors to Cliff Granberry Corporation,
Dallas, Tex., a corporation of Texas

Filed Dec. 26, 1967, Ser. No. 10,265

Term of patent 14 years

Int. Cl. D25—04

U.S. Cl. D13—1

Fig. 1

Fig. 2

Fig. 3

Fig. 4

FIGURE 1 is a perspective view of the waste hopper showing our new design;

FIGURE 2 is a fragmentary end view in perspective of the upper portion of the opposite end of the hopper of FIGURE 1;

FIGURE 3 is a top plan view thereof; and

FIGURE 4 is a side elevation of one side of the waste hopper of FIGURE 1, the opposite side being the identical reverse thereof.

We claim:

The ornamental design for a waste hopper, substantially as shown and described.
